UNITED STATES PATENT OFFICE.

FRANK MOSSBERG, OF PROVIDENCE, RHODE ISLAND, ASSIGNOR TO MOSSBERG
PRESSED STEEL CORPORATION, OF ATTLEBORO, MASSACHUSETTS, A CORPORATION
OF MASSACHUSETTS.

CARRIER FOR BRAIDING MACHINES.

Application filed April 29, 1921. Serial No. 465,528.

This invention relates to improvements in yarn carriers for braiding machines, and has for its object to provide such a carrier having an improved movable yarn tension and 5 take-up member.

A further object of this invention is the provision of a spring-actuated yarn take-up member which is mounted to swing or oscillate about the axis of the package and 10 around which member the yarn is led to apply the required tension thereto and serve to take up the intermittent slack in the yarn due to the zigzag course of the carrier.

With these and other objects in view, the 15 invention consists of certain novel features of construction, as will be more fully described, and particularly pointed out in the appended claims.

In the accompanying drawing:

20 Figure 1 is a side elevation partly in section illustrating my improved carrier with the yarn take-up in position to apply a tension to the yarn; also showing the bearing for the detent in section. Figure 2 is a view 25 from the opposite side of the carrier illustrating the cam on the take-up member for controlling the let-off action of the detent.

Figure 3 is a central section through the 30 hub of the take-up, showing the spring for operating the same.

Figure 4 is a top view of the device sectioned on line 4-4 with the yarn package shown in dotted lines.

Figure 5 is a perspective view showing a 35 detail of the stop plate and its eye wire.

It is found in practice in the construction 40 of carriers which are designed to run at a very high rate of speed through the serpentine raceway of a braiding machine, that quick operating means should be provided for exerting a practically uniform tension 45 on the yarn while the carrier is following its zigzag course in which its distance from the braiding point varies; also that the supply of yarn shall be released to permit the necessary quantity to be drawn off as required, and the following is a detailed description of one means by which this result may be accomplished:—

50 With reference to the drawing, 10 designates the base portion of a carrier upon which is mounted the usual yarn-package-supporting-spindle, the lower end of which

spindle is preferably slightly enlarged as at 55 12. On this enlarged portion I have mounted a sleeve 13 which has an enlarged central recess 14 in which is mounted a coiled tension spring 15. One end 16 of the spring extends through the side wall of the hub while the opposite end 17 extends through a fixed 60 collar 18 which is secured to the enlarged portion of the spindle preferably by being threaded thereon. This collar 17 also serves as an upper bearing for the hub while the lower portion 19 of the hub receives a bearing 65 directly upon the enlarged portion of the spindle.

On one side of the hub member is a boss 20 in which is secured the lower right-angled 70 end of the upright tension rod 21. This tension rod extends upwardly along and adjacent to the face of the yarn package 22 so that the yarn 23 in being drawn from the package may be led around this rod as hereinafter more fully described.

On the side of this hub 13 opposite to that 75 of the boss 20 I have formed a cam member 24 best shown in Figure 2.

In order to hold my yarn package against 80 rotation due to the tension of the yarn thereon, until such time as it is required that more 85 yarn shall be let off from the package, I preferably provide a set of ratchet teeth 25 on the lower end of the package and I also provide a pawl or detent 26 arranged to engage 90 these ratchet teeth for the purpose described. This pawl, detent, or latch, I have shown as being made in the form of a pin 27 mounted to slide vertically in the bearing 28 normally pressed upward into engagement with the teeth by means of the spring 29 and in order to limit the rising motion of this detent I have provided a stop pin 30 adapted to slide in the slot 31 in the bearing 95 28. The inner end of this pin 30 extends into the path of movement of the cam 24 to be engaged thereby as the take-up sleeve 13 is rotated in one direction by an increasing tension on the yarn.

On the end of the base opposite to that of 100 the detent latch I have mounted a standard 32, the upper end of which is provided with a guide eye 33 through which the yarn 23 is led. On the lower end of this standard I have mounted a stop plate 34 the same being 105 provided with a guide hole 35 through

which the standard 32 extends and a guide hole 36 through which a guide pin 37 extends. This plate is also provided with an upstanding eye wire 38 having an eye 39 which extends around the standard 32, the eye 40 or loop of this standard-engaging portion being of sufficient size to also serve as a guide eye for the yarn which is threaded therethrough to hold the plate normally in raised position when the yarn is under tension. The inner edge of this plate is provided with a pair of downwardly extending lips 41 which when the plate is down due to excessive slack or a breakage in the yarn, are adapted to engage the usual stop mechanism on the braider to arrest the motion of the machine.

In the operation of my improved carrier it will be seen that in threading up the carrier the yarn is led from the package around the tension rod 21 through the eye 40 in the eye wire 38 and up through the guide eye 33 in the standard 32. In this way when the yarn slackens, due to an inward motion of the carrier, towards the braiding center, the rod moves in the arc of a circle to the left under action of the tension spring 15, thereby maintaining the required uniform tension on the yarn.

As the yarn last let off from the package is now being used up the tension rod works naturally towards the right and when it is drawn to a predetermined point in this direction, the cam 24 on the sleeve 13 of the take-up, engages the pin 30 and withdraws the detent 26 from engagement with the teeth 25 on the package, thereby permitting the package to move under tension of its yarn to let off the required amount of yarn and as soon as the tension on the yarn is released the tension rod 21 moves back to the left about the axis of the package causing its cam 24 to again release the detent permitting it to rise and engage the next tooth of the package and so prevent the letting off of an excessive amount of yarn. In this way the tension on the yarn is nicely controlled and at the same time the proper amount is automatically fed from the package.

My improved takeup and tension device is extremely simple and inexpensive in construction and effective in its operation and by its use a substantially constant tension is maintained on the yarn during its serpentine travel through the raceway of a machine and only the desired quantity of yarn is drawn from the cop each time a fresh draft is made on the supply.

The foregoing description is directed solely towards the construction illustrated, but I desire it to be understood that I reserve the privilege of resorting to all the mechanical changes to which the device is susceptible, the invention being defined and

limited only by the terms of the appended claims.

I claim:

1. A carrier for braiding machines having a vertical spindle on which a yarn package 70 is rotatably mounted, means for controlling the rotation of the package, and a vertically-disposed yarn take up member having a yarn engaging portion mounted to rotate about the axis of the package. 75

2. A carrier for braiding machines having a vertical spindle on which a yarn package 80 is rotatably mounted, means for controlling the rotation of the package, and a vertically-disposed yarn take up member having a yarn engaging portion located intermediate the ends of the package and mounted to rotate about the axis of the package. 85

3. A carrier for braiding machines having a vertical spindle on which a yarn package of substantial length is rotatably mounted, and a vertically arranged yarn take up member having a yarn engaging portion of substantial length supported from a point 90 below the package and to rotate about the axis of the package. 95

4. A carrier for braiding machines having a rotatable yarn package mounted thereon, a detent for said package, a spring-pressed yarn take-up member mounted below said package to swing about the axis of said package, and means located below said package on said take-up for operating said detent to release said package. 100

5. A carrier for braiding machines having a rotatable yarn package mounted thereon, a spring-pressed detent for said package, a spring-actuated yarn take-up member mounted on a rotatable sleeve below said 105 package to move about the axis of said package, and a cam on said sleeve for operating said detent to release said package.

6. A carrier for braiding machines having a vertical yarn package rotatably mounted thereon, a detent for controlling the rotation of said package, a vertically disposed movable rod extending along the face of said package over which the yarn is led from the package, and means for causing said 110 rod to be revolved about the axis of the package to take up the slack of the yarn.

7. A carrier for braiding machines having a vertical yarn package rotatably mounted thereon, a detent for said package, a vertically disposed movable member extending longitudinally along the face of said package over which the yarn is led to take up its slack, and means operated by the movement of said member in one direction 120 for causing a release movement of said detent. 125

8. A carrier for braiding machines having a yarn package rotatably mounted thereon, a detent for said package, a rotatable 130

sleeve mounted beneath said package, a yarn take-up standard extending along the face of the package, and means whereby the rotating of said sleeve and standard controls the releasing action of said detent.

9. A carrier for braiding machines having a yarn package rotatably mounted thereon, a detent for said package, a rotatable

spring actuated sleeve mounted beneath said package, a yarn take-up standard carried by said hub to move about the axis of said package, and a cam on said sleeve for causing said detent to release said package when more yarn is required.

In testimony whereof I affix my signature.
FRANK MOSSBERG.
